UNITED STATES PATENT OFFICE

114,698

DESIGN FOR AN ILLUMINABLE VANITY CASE OR SIMILAR ARTICLE

George M. Cressaty, New York, N. Y.

Application June 14, 1938, Serial No. 77,833

Term of patent 14 years

To all whom it may concern:

Be it known that I, George M. Cressaty, a citizen of France, residing at New York, in the county of New York and State of New York, have invented a new, original, and ornamental Design for an Illuminable Vanity Case or Similar Article, of which the following is a specification, reference being had to the accompanying drawing, forming part thereof.

Fig. 1 is a top perspective view of an illuminable vanity case or similar article, in open position, embodying my new design.

Fig. 2 is a fragmentary sectional view thereof on the line 2—2 of Fig. 1.

The dominant features of my design reside in the portions shown in full lines.

I claim:

The ornamental design for an illuminable vanity case or similar article, substantially as shown and described.

GEORGE M. CRESSATY.
